UNITED STATES PATENT OFFICE.

MICHAEL O. FINKBEINER, OF MYRTLE, CALIFORNIA.

DESIGN FOR A CAN-OPENER.

SPECIFICATION forming part of Design No. 30,615, dated April 25, 1899.

Application filed March 18, 1899. Serial No. 709,687. Term of patent 7 years.

To all whom it may concern:

Be it known that I, MICHAEL O. FINKBEINER, a citizen of the United States, residing at Myrtle, in the county of Los Angeles and State of California, have invented and produced a certain new and original Design for Can-Openers; and I do declare the following to be a full, clear, and exact description of the invention, such as will enable others skilled in the art to which it appertains to make and use the same.

My invention has relation to a new and original design for can-openers; and it consists of a design of the configuration shown in the accompanying drawings, in which—

Figure 1 is a perspective view, and Fig. 2 is a longitudinal sectional view.

The leading feature of the design comprises

a handle 1, from which projects a shank 2, the forward end of which has parallel overlapping rectangular enlargements 3 and 4, the latter of which terminates in a flat heart-shaped blade 5, the point of which projects forwardly beyond the forward ends of the enlarged portions 3 and 4. 25

What I claim is—

The design for a can-opener, as herein shown and described.

In testimony whereof I have hereunto set my hand in presence of two subscribing witnesses. 30

MICHAEL O. FINKBEINER.
